(57) **CLAIM**

The ornamental design for an instrument panel for an automobile or replica, as shown and described.

DESCRIPTION

FIG. 1 is a front and left side perspective view of an instrument panel for an automobile or replica showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The claimed design is indicated by the relatively dark portions in the figures, while the relatively light portions are environmental structures and form no part of the claimed design. The drawings include grayscale surface shading which illustrates contour, not any particular color.
